UNITED STATES PATENT OFFICE.

THOMAS P. MARTIN, JR., OF OKLAHOMA, OKLAHOMA.

PASS-BOOK.

1,352,907.

Specification of Letters Patent. Patented Sept. 14, 1920.

Application filed April 8, 1919. Serial No. 288,520.

To all whom it may concern:

Be it known that I, THOMAS P. MARTIN, Jr., a citizen of the United States, and a resident of Oklahoma city, in the county of 5 Oklahoma and State of Oklahoma, have made certain new and useful Improvements in Pass-Books, of which the following is a specification.

My present invention relates generally to 10 bank pass books, and more particularly to a pass book construction which embodies a detachable inner pad in order to allow of renewal from time to time, my primary object being the provision of a novel construction 15 of cover permitting of ready use of the ordinary pass book pad in such manner as to show the depositor's name through a window in the cover and in addition thereto identify, if desired, the particular account or ac- 20 counts for which the pass book is issued.

These objects and the particular construction proposed by my invention for carrying the same out, will be better understood from the following description, referring to the 25 accompanying drawing forming a part of this specification, and wherein:—

Figure 1 is a rear or outside elevation of the pass book in open position with the pad in place;

Fig. 2 is a front or inside elevation of the pass book of Fig. 1;

Fig. 3 is a sectional view taken on the line 3—3 of Fig. 1;

Fig. 4 is another sectional view taken on the line 4—4 of Fig. 3;

Fig. 5 is an elevation of the pad of Figs. 1 and 2 removed;

Fig. 6 is a perspective view of another form of pad;

Fig. 7 is a perspective view illustrating the most simple form of the invention;

Fig. 8 is an inside face view of the cover;

Fig. 9 is an elevation of the pad;

Fig. 10 is an inside face view illustrating 45 a slightly modified form;

Fig. 11 is a view of a portion of another modified form, and

Fig. 12 is a view of a modified form of pad.

Referring now to Figs. 1 to 6 inclusive, my invention proposes a pass book embodying a cover generally indicated at 10, and a pad which may be of several forms, as for instance the pad 11 of Fig. 5, which is also

shown in Figs. 1 and 2, in connection with 55 the cover 10, and a pad generally indicated at 12 in Fig. 6.

The cover 10 has a front 13 and a back 14, and is provided with a sight opening 15 either in the front 13 only, or has an additional sight opening 16 in its back 14, where it is intended to be reversible in order that two accounts may be carried in the same pass book, as presently described.

In the reversible form, the pass book is of 65 the same construction as when used for but a single account, and a description of its construction as applied to the window or opening 15 will therefore suffice for a thorough understanding in view of the fact that the 70 sight opening or window 16 is but a duplication on the back 14 of the construction to be now described in connection with the front 13.

Referring now to Figs. 3 and 4, which 75 show the construction of the front 13 providing for the advantage to be presently described, the front 13 has its sight opening 15 cut through its covering material 17, as well as its inner stiffening layer 18 to register 80 with a slot of greater width than the opening 15 formed within an inner layer 19, which slot receives and supports an insiglass or celluloid piece 20, or other transparent covering, as well as the tongue 21 of 85 a pass-book tab formed as presently described. The front 13 includes an outer wall consisting of the outer covering 17, stiffening layer 18, inner layer 19, and an inner covering 22, and an inner wall consisting of inner 90 and outer layers 25, these inner and outer walls forming an enlarged pocket opening inwardly along the central portion of the book cover.

Next to the inner layer 19 is the inner 95 covering 22 just referred to, which has a slit at the inner end of the window 15, and the inner end of the slot in the inner layer 19, to provide for the introduction of the tongue 21 behind the transparent covering 20 and in 100 position registering with the window or sight opening 15 to show the name of the owner of the account, and if desired, data identifying the particular account where the owner has more than one account. The slit 105 of the inner covering 22 appears in Fig. 4, where the tongue 21 is seen within the space between the inner covering 22 and the trans-

parent covering 20, the slotted opening of the inner layer 19 forming a pocket to receive and retain the transparent covering 20 and also the tongue 21. In the figure last mentioned, the tongue 21 furthermore is seen as projecting from a portion 23 of the pad, a leaf or portion 24 of which enters the enlarged pocket or compartment formed between the outer and inner walls of the cover 10 and opening along its inner edge adjacent the center of the cover as above described, and which is of course duplicated upon the inner surface of the back 14.

In providing for the tongue 21, a pass book pad 26, as seen in Fig. 6, may have specially formed outer leaves, each including a lower enlarged portion 27 and an upper tongue 28, the latter of which corresponds to the tongue 21 of Figs. 3 and 4, and the former of which corresponds to the remainder 24 of the outer leaf of the pad. As far as pass book construction is concerned, a duplicate form of that shown in Figs. 3 and 4 is illustrated in Fig. 5, the upper portion 25 where the account owner's name appears being cut free from the lower portion along the dotted line 29, so as to form the upper tongue 21. A section of one end, as indicated at 30, outwardly beyond the dotted line 31, is then cut away, leaving a portion 24, which extends into the enlarged pocket of the cover and co-operates with the tongue extending behind the sight opening, to hold the pad in place in the cover.

It is thus to be seen that my invention is capable of ready duplication and use in connection with both the front and back of a pass book cover 10, particularly in connection with a pad such as indicated at 31 in Fig. 40, ruled and readable in relatively opposite directions from its center, so that when placed within the cover, the latter reads correctly in upright position for each of two accounts, it being apparent that due to their 45 location adjacent relatively opposite ends of the cover, one of the sight openings 15 and 16 will appear uppermost in either of the reversed positions of the cover.

My invention also provides for the use 50 of the ordinary pass book pad simply cut at the outer page or pages thereof along the dotted lines 29 parallel to the upper edges and below the space where the account owner's name is usually written, so as to form the necessary tongue for projection between the inner covering 22 of the cover and the sight opening 15, while the remainder of the outer page or pages are projected within the inner enlarged pockets of the cover.

The most simple form of my invention is exemplified in Figs. 7, 8 and 9, wherein the cover 35 of Figs. 7 and 8, has its outer wall provided with a sight opening 36 at one side and has inner walls 37 at its opposite 60 sides forming inwardly opening pockets for

the reception of the outer pages or stiffened sheets 38 of a pad 39 as seen in Fig. 9, the name of the depositor being written or printed on the outer face of one of the sheets 38 as seen in dotted lines in Fig. 9, to show 70 through the window or sight opening 36, as in Fig. 7.

As seen in Fig. 10, the cover 40 may have an additional opening 41 through one of its inner pocket forming walls 42 so that the 75 name of the depositor written or printed at 43 on the inner surface of one of the outer pages or stiffened sheets of the pad 44 will show when the cover is open. This form of the invention is otherwise constructed as described in connection with Figs. 7 to 9 inclusive.

According to the form of Figs. 11 and 12, the cover 45 of Fig. 11 has its outer and inner walls provided at one side with alined 85 openings 46, the pad itself having the depositor's name thereon as seen at 47, in the usual place to show through the alined openings. This is accomplished by cutting away that portion of one of the outer pages or 90 stiffened sheets 48 of the pad 49 as seen particularly at 50 in Fig. 12, which would otherwise obstruct the view through the openings 46.

It is obvious from the foregoing that my 95 invention is capable of various changes and modifications of which the most important only have been shown and particularly described.

I claim:—

1. A pass book cover having inner and outer walls forming an enlarged inwardly opening pocket upon one portion thereof, the outer wall having an outer covering provided with a sight opening adjacent one end, 105 and an inner covering between the pocket and the sight opening, said outer wall including an inner layer and an inner covering between the sight opening and the said pocket, the inner layer being provided with a slot opposite the sight opening and the 110 said inner covering being provided with a slit adjacent the inner end of the sight opening through which access may be had to the slot of the said inner layer from the pocket 115 of the cover.

2. A pass book including a pad having an outer tongue formed thereon to receive the name of the account owner, and a cover having inner and outer walls forming an enlarged pocket opening along the central portion of the cover to receive the outer page of the pad and the said tongue, said outer wall including an outer covering having a sight opening adjacent one end to aline with the 120 tongue and provided with an inner layer having a pocket opposite the sight opening to receive the said tongue, and an inner covering between the inner layer and the 125 said pocket which is slotted adjacent to the 130

inner end of the sight opening to permit the tongue to be extended into the slot of the inner layer of the cover, as described.

3. A pass book including a pad having 5 its outer page separated to form a tongue at one end on which the name of the account owner appears, and a cover having inner and outer walls forming an inwardly opening 10 pocket to receive the said outer page of the pad and its tongue, said outer wall of said cover including an outer covering having a sight opening adjacent one end and an inner layer provided with a slot opposite the sight opening, a transparent covering 15 for the sight opening, said slot of said inner layer forming a pocket to receive the said transparent cover and the tongue of the pad, and said outer wall also including an inner covering between the said inner layer 20 and the outer page of the pad lying within the first mentioned pocket, said inner covering having a slot adjacent to the inner end of the sight opening to permit of the introduction of said tongue within the pocket 25 of the inner layer, as described.

4. A pass book for bank depositors including a cover and a detachable pad therein having tongues forming name spaces for the name of the depositor, the cover having inner and outer walls forming inwardly open-

ing pockets receiving the outer pages of the pad and said tongues, and said outer walls being provided with sight openings for exposing the name space of the pad to view through the cover and with 35 tongue receiving pockets adjacent to said sight openings.

5. A pass book for bank depositors including a cover and a detachable pad therein having outer leaves one of which is provided with a space for the name of the depositor, the cover having inner and outer walls forming pockets at its opposite sides opening toward one another for the reception of the outer leaves of the pad, said outer wall at one side being provided with a sight opening through which the said name space 40 is exposed.

6. A pass book for bank depositors, including a cover and a detachable pad therein having a name space for the name of the depositor, the cover having inner and outer walls forming inwardly opening pockets to receive the outer leaves of the pad, one of 50 said outer walls of said cover having a sight 55 opening through which the name space of the pad is exposed when said pad is properly positioned within the cover.

THOMAS P. MARTIN, JR.
